(57) **CLAIM**

The ornamental design for a battery pack as shown and described.

DESCRIPTION

FIG. 1 is a front, right, bottom perspective view of a battery pack according to the present application, showing our new design;

FIG. 2 is a front, left, top perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is an enlarged partial view of the area identified as 9 in FIG. 3;

FIG. 10 is an enlarged partial view of the area identified as 10 in FIG. 4;

FIG. 11 is an enlarged partial view of the area identified as 11 in FIG. 5; and,

FIG. 12 is an enlarged partial view of the area identified as 12 in FIG. 6.

The broken line showing of a battery pack is included for the purpose of illustrating portions of the article and forms no part of the claimed design. The long-dashed broken lines in FIGS. 3-6 and FIGS. 9-12 are for the purpose of indicating the area of the enlarged views and form no part of the claimed design.
